CARPET.

No. 18,129.

Patented Mar. 6, 1888.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 18,129, dated March 6, 1888.

Application filed January 26, 1888. Serial No. 962,051. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design consists of masses or groups of irregular outline made up of small geometrical

figures of various shapes. These groups vary in size and form and are arranged in an irregular manner over the face of the carpet. 20 The edges of these groups curve in and out, forming an irregularly scalloped outline. Around each group is a border or margin of shadow-like work, the outline of which corresponds with the outline of the group. 25

What I claim as new, and desire to secure by Letters Patent, is—

The design for carpets, consisting of the design substantially as shown.

JAS. L. FOLSOM.
